UNITED STATES PATENT OFFICE.

NICHOLAS D. CHARD, OF CINCINNATI, OHIO, ASSIGNOR TO THE LODGE & SHIPLEY MACHINE TOOL COMPANY, OF CINCINNATI, OHIO, A CORPORATION.

VARIABLE-SPEED MECHANISM.

SPECIFICATION forming part of Letters Patent No. 744,678, dated November 17, 1903.

Application filed July 28, 1903. Serial No. 167,364. (No model.)

To all whom it may concern:

Be it known that I, NICHOLAS D. CHARD, a citizen of the United States, residing at Cincinnati, in the county of Hamilton and State 5 of Ohio, have invented certain new and useful Improvements in Variable-Speed Mechanism, of which the following is a specification.

My invention relates to a speed-variator in which a plurality of different-diameter gear-wheels are disposed on parallel shafts and intermeshed, means being provided for simultaneously clutching any selected pair of intermeshed gear-wheels to their two shafts, respectively.

15 My invention particularly relates to the construction and arrangement of the keys by means of which the clutch is effected.

The features of my invention are more fully set forth in the description of the accompanying drawings, making a part of this specification, in which—

20 Figure 1 is a central horizontal section, partly in elevation, of my device. Fig. 2 is an enlarged sectional view of the shifting 25 clutch mechanism. Fig. 3 is a section on line $\alpha\alpha$, Fig. 2, but showing the gear-wheel mounted in elevation on the shaft. Fig. 4 is an enlarged detailed diagram view in section, showing the relation of the engaging keys of shifting member and gears. Fig. 5 is a side elevation of my improvement. Fig. 6 is an end view. Fig. 7 is a detail plan view of the cam-disk. Fig. 8 is a detail sectional view of the sleeve, actuating-gears, and disks. Fig. 9 is 30 a detail plan view of the devices shown in Fig. 8.

35 1 represents the casing, in which are journaled the parallel shafts 2 3. The casing is provided with arms 4, having collars containing the Babbitt metal 5, forming a journal-bearing for the hubs of the oppositely-intermeshing gear-wheels 7 8 9 10 11 12 13 14 and 15 16 17 18 19 20 21 22, supported in said collars loosely relative to their concentric shafts 40 2 and 3. The collars are provided with oil-duets a , formed therein and at the abutting position of the gear-wheel hubs.

45 23 represents a gear-wheel on the driving-shaft 2 for rotating the same, and 24 represents a pulley-wheel on driven shaft 3 for conveying the power to the machine on the floor.

25 represents the shifting members. As shown and preferred, they are sleeves sliding on shafts 2 and 3. Their projecting ends are provided with rack-teeth 26. 27 28 represent 55 intermediate intermeshing gear-wheels meshing also with the rack-teeth 26 and constituting the means for simultaneously shifting said sleeve 25. The gear-wheels are bored to a diameter loosely fitting the diameter taken 60 through the keys on the shifting sleeve. The gear-wheel bores are provided with one or more internally-projected keys 29 and the shifting sleeve with a corresponding number of externally-projected keys 31. Both gear- 65 wheel and sleeve keys are beveled at both ends so as to slip into interlocking relation when axially presented. One key could be employed, if desired; but preferably four are employed, as shown. The keys 31 on the sliding sleeve of the driven shaft 3 are placed opposite the keys on the sleeve of the driving-shaft, but extending beyond the same at each end. This is indicated by diagram in Fig. 4. The sleeves 25 are preferably two-partsleeves, 70 as shown in Fig. 2, each sleeve having a member 30, carrying the keys. These members are secured by the internal coupling collar-section 32, so that they slide in unison on their contained shaft; but the member 30 is 75 rotatable and keyed to the shaft. As a result of the arrangement of keys 31 when the keys of the sleeves are presented to the keys of the gear-wheels the keys on the driven shaft 3 will be first presented in either direction of movement of sleeves, as shown in diagram, Fig. 4, in which the key of the sleeve on the driven shaft is already engaging with the key 29 of the driven gear-wheel before the key 31 of the driving-sleeve has been presented to the key 29 of the driving gear-wheel. Therefore the keys of the driven sleeve will be already partially engaged, fixing the selected driven gear-wheel to the driven shaft before the selected driving gear-wheel has 80 85 been keyed to its shaft. This prevents all binding or shock to the keys.

33 represents the main driving-shaft, from which power is conveyed to the shafts 2 and 3, bearing the variable-speed gear-wheels.

90 34 and 35 represent driving right and left hand pulley-wheels loose on shaft 33 and

adapted to be fixed thereto by the shifting clutch 36.

38 represents a lever pivoted to the casing and engaging rod 37 for controlling the clutch 36. (See Fig. 5.)

39 represents a gear-wheel on the end of the shaft 33.

40 represents an intermediate gear-wheel journaled in the end of the casing and connecting in train gear-wheel 39 on shaft 33 and gear-wheel 23 on shaft 2. Gear-wheel 23 is loose on shaft 2 and disconnected therefrom and connected thereto by means of the shifting clutch 41.

42 represents a rod for shifting the clutch 41. Following is the description of the mechanism for shifting the sleeves 25 and for shifting the clutch-rod 42.

43 represents a turning rod provided with a handle 44. One of the gear-wheels 28 is loose on the turning rod 43. The other gear-wheel 27 is loose on a short stub-shaft 45. (See Fig. 6.)

53 represents a fragment gear-wheel fixed on turning rod 43. Gear-wheel 27 on stub-shaft 45 is equal in face width to both gears 28 and 53, with both of which it meshes. The fragment-gear 53 is spaced to move the keys 31 in positive steps, either into gears from an intermediate idle position or out of gears into an intermediate idle position. These gear-wheels 27 53 have the projecting hubs 46, (see Fig. 6,) which are provided with the interlocking disks 47, which have coacting projections and recesses 48 and 49, as shown in Fig. 9, the function of which is to lock the gear-wheels 53 and 27 in their positions of rest.

50 represents a cam-disk mounted on the turning rod 43 and having the cam-groove 51, as shown in Fig. 7.

52 represents a rod connected to the rod 42 at one end and the other end being provided with an antifrictional roller engaging with the cam of the cam-disk 50.

45 Assume the keys 31 to be in position fixing any selected pair of gear-wheels—say 8 and 16—to the shafts 2 and 3, respectively. If it be desired to make a change of position, handle 44 is rotated in the proper direction.

50 In the first part of this rotation through the instrumentality of the cam-disk 50 and the shifting rods 52 and 42 the clutch 41 is disengaged, leaving the gear-wheel 23 loose on shaft 2. Therefore the following sliding of the keys on their shafts occurs while the shafts 2 and 3 are free from the load. When the keys 31 begin their new engagement, one sliding in advance of the other, they become fixed on the gear-wheels while the load is still off.

60 The completion of the rotation of the handle 44 throws in the clutch 41. The intermeshing of the interlocking disks 47 locks the gear-wheels 27 and 53 in position with the keys 31 either in an intermediate position between two given gear-wheels or in position of engagement with a selected pair of gear-wheels.

It will be understood that the keyed sleeve in the driven shaft is stationary while the keyed sleeve on the driving-shaft is rotating therewith and that by the elongation of the keys on the driven sleeve it is insured that the stationary or driven gear-wheel will be keyed to its shaft before the driving gear-wheel is keyed to its shaft. Hence when the key of the driving-sleeve is engaged into a selected driving gear-wheel, fixing it to its shaft, it finds that the driven keyed sleeve has already fixed the opposite driven gear-wheel to its shaft, and hence both gear-wheels start their rotation without any jar and without the danger of binding or smashing the keys which would be apt to occur if these driving and driven keyed sleeves were presented absolutely simultaneously to the gear-wheel keys for interlocking. This is an important and necessary feature in practice essential to a smooth and safe operation.

Having described my invention, I claim—

1. In a speed-variator, a shaft, a series of loosely-mounted gear-wheels of different diameter, a member shifting internally of the gears, the gears having an internally-projected hub-key, the shifting member having an externally-projected peripheral key, and said keys being tapered at their ends to pass when axially presented and to interlock when rotatively presented, substantially as specified.

2. In a speed-variator, a pair of shafts, intermeshing gear-wheels of different diameter loosely supported relative to the said shafts, oppositely-disposed keys on said shafts internal of the gears, tapered at their ends, one of said keys overlapping its opposing key at each end, and means for shifting said shafts, substantially as specified.

3. In a speed-variator, a pair of shafts, intermeshing gear-wheels of different diameter loosely supported relative thereto, oppositely-disposed keys on said shafts, adapted to fix any selected pair of intermeshing gear-wheels to their respective shafts, said keys being tapered at their ends, the key on the driven shaft extending beyond each end of the coacting key on the driving-shaft whereby it travels slightly in advance of the shorter key in axial movements, and means for shifting said keys, substantially as specified.

4. In a speed-variator, a pair of shafts, intermeshing gear-wheels of different diameter loosely supported relative thereto, the hubs of said gears having internally-formed keys, shifting members on said shafts internal of said gears hitched to travel in unison, keys peripherally formed on said shifting member, said keys being tapered at their ends to pass when axially presented and to interlock when rotatively presented, and means for shifting said shifting members, the keys on one of said shifting members being projected in the direction of the axis beyond the ends of the keys on the opposing shifting member, whereby in either direction of axial movement the

keys of one of the shifting members engage the gear-wheel keys first, substantially as specified.

5. In a variable-speed device, two parallel shafts, intermeshing pairs of different-diameter gear-wheels loose thereon, sliding keys between said gear-wheels and shafts, racks for sliding said keys, a turn-rod, a gear-wheel loose thereon, a gear-wheel fixed thereon, a stud-shaft, a gear-wheel thereon in mesh with both gear-wheels on the turn-rod, said gear-wheels forming a driving-train between said racks, substantially as specified.

6. In a variable-speed device, two parallel shafts, intermeshing pairs of different-diameter gear-wheels loose thereon, sliding gear-keys between said gear-wheels and shafts, racks for sliding said keys, a turn-rod, a fast and loose gear-wheel thereon, a stud-shaft, a gear-wheel thereon in mesh with said turn-rod gear-wheels, said gear-wheels connecting in train said racks, and one of said gear-wheels being a fragment-gear for sliding the keys in positive step movements, substantially as specified.

7. In a variable-speed device, two parallel shafts, intermeshing pairs of different-diameter gear-wheels loose thereon, sliding keys between said gear-wheels and shafts, racks for sliding said keys, a turn-rod, a parallel stud-shaft, intermeshing gear-wheels thereon connecting in train the racks, a driving-wheel on one of the main shafts, a clutch between said main shaft and driving-wheel, a cam on said turn-rod, and connections between said cam and clutch for shifting the clutch intermediate of the sliding of the keys, substantially as specified.

8. In a variable-speed device, two parallel shafts, intermeshing pairs of different-diameter gear-wheels loose thereon, sliding keys between said gear-wheels and shafts, racks for sliding said keys, a turn-rod, a parallel stud-shaft, a train of intermeshing gear-wheels between said rod and stud-shaft in mesh with said racks, one of said train being a fragment-gear to slide the keys in step movements, a power-wheel on one of said main shafts for driving, a clutch between said shaft and wheel, a cam on said turn-rod, and connections between said cam and clutch to shift the clutch in time movements relative to the step movements of the sliding keys, substantially as specified.

9. In a variable-speed device, two parallel shafts, intermeshing pairs of different-diameter gear-wheels loose thereon, sliding keys between said gear-wheels and shafts, racks for sliding said keys, a turn-rod, a parallel stud-shaft, a train of intermeshing gear-wheels between said rod and stud-shaft in mesh with said racks, one of said train being a fragment-gear to slide the keys in step movements, interlocking disks on said turn-rod and stud-shaft to partially lock the gears in their steps, substantially as specified.

10. In a variable-speed device, a driving-

shaft, two parallel shafts, pairs of intermeshing gear-wheels of different diameter loose on said parallel shafts, keys sliding between said gear-wheels and their shafts; a train of gear-wheels between said driving-shaft and one of said parallel shafts, clutch mechanism mounted on said parallel shaft in clutching relation with one gear-wheel of said train of gear-wheels, mounted on said parallel shaft for imparting motion thereto, and means for shifting said clutch, before and after the shifting of said keys, substantially as specified.

11. In a speed-variator, a pair of shafts, intermeshing pairs of different-diameter gear-wheels loosely supported relative thereto, clutches sliding inside of said gear-wheel bores adapted to fix any pair of intermeshing gear-wheels to their shafts, the said gear-wheels being of greater width than the said sliding clutches, whereby an intermediate idle position is given the latter, means for driving one of said shafts, and means for simultaneously shifting the said clutches in positive step movements into and out of the gear-wheel bores, substantially as specified.

12. In a speed-variator, a shaft, a two-part sleeve thereon, one of said sleeves being fixed to turn with and slide on said shaft, the other sleeve being fixed to the rotary sleeve member so as to slide therewith on the shaft without turning, a plurality of different-diameter gear-wheels loosely supported relative to the said sleeve, the rotary sleeve member having a keyed engagement independently with each of the gear-wheels, whereby any gear-wheel is fixed to its shaft, and means for shifting the said sleeve on said shaft, substantially as specified.

13. In a speed-variator, a shaft, a two-part sleeve thereon, one of said sleeves being fixed to turn with and slide on said shaft, the other sleeve member being fixed to the rotary sleeve member so as to slide therewith on the shaft without turning, a plurality of different-diameter gear-wheels loosely supported relative to the said sleeve, the rotary sleeve member having a keyed engagement independently with each of the gear-wheels, whereby any gear-wheel is fixed to its shaft, means for shifting the said sleeve on said shaft, the said rotary sleeve member being of the width of each of the gear-wheels, and the said gear-wheels being spaced the width of the rotary sleeve, whereby the clutch is given an intermediate idle position, substantially as specified.

14. In a speed-variator, a pair of shafts, a pair of gear-wheels of different diameter loosely supported relative to said shafts, a shifting member for each shaft loosely fitting the diameter of the gear-wheel bores, the said shifting members, having a plurality of diametrically-opposed keys, and each gear-wheel bore having a corresponding number of keys, the keys being tapered at their ends to automatically pass when the shifting members are axially presented to a given pair of gear-

wheels, means for actuating said shifting members simultaneously, means for driving one of said shafts, a clutch for controlling the said drive, and means for shifting the said driving-clutch, whereby the shifting members of the differential gear-wheels are moved when the drive is off, substantially as specified.

15. In a speed-variator, a pair of shafts, in-
termeshing pairs of gear-wheels of different
diameter loosely supported relative to said
shafts, means for driving one of said shafts, a
shifting clutch controlling said drive, clutches
sliding within the bores of said gear-wheels
adapted to fix any selected pair to their shafts,
said gear-wheel clutches having racks, an op-
erating-rod, a train of gear-wheels actuated
by said rod and intermeshing with said racks
to shift the differential gear-clutches simulta-
neously, and cam shifting devices actuated
by said rod to shift the driving-clutch after
a selected pair of intermeshing gear-wheels
have been clutched to their shafts, substan-
tially as specified.

25. 16. In a speed-variator, a shaft, a series of
speed-changing gear-wheels loosely support-
ed relative thereto, a shifting member sliding
within the bores of said gear-wheels, the meet-
ing surfaces of said bores and said shifting
30 member having a plurality of interlocking
keys tapered at their ends, whereby the shift-
ing member is adapted to fix each of said gear-

wheels to said shaft when axially presented
thereto, and means for actuating said shift-
ing member, substantially as specified.

35

17. In a speed-variator, a pair of shafts hav-
ing intermeshing pairs of different-diameter
gear-wheels loosely supported relative there-
to, sliding clutches within said gear-wheel
bores, oppositely placed on said shafts, said 40
clutch members having lateral extensions pro-
vided with rack-teeth, an operating-rod, and
a train of gear-wheels between said operat-
ing-rod and rack-teeth adapted to simultane-
ously shift said clutches in either direction, 45
one of said train of gears being a fragment-
gear adapted to actuate said shifting clutches
in step movements, substantially as speci-
fied.

18. In a speed-variator, a frame, a shaft a 50
series of gear-wheels thereon each having ex-
tended hubs the ends of which abut, bearing-
collars supported by the frame and interposed
between said gear-wheels and forming bear-
ings for said hubs, and oil-duets formed in 55
the bearing-surfaces of said collars, substan-
tially as specified.

In testimony whereof I have hereunto set
my hand.

NICHOLAS D. CHARD.
